UNITED STATES PATENT OFFICE.

CHARLES E. CAMPBELL, OF LYNN, MASSACHUSETTS.

X-RAY APPARATUS.

Application filed August 25, 1921. Serial No. 495,395.

The present invention relates to X-ray apparatus, and more particularly to apparatus of a type commonly employed by physicians, surgeons and other practitioners for viewing or taking radiographs of parts of the human body, and for other purposes.

In a copending application, Serial No. 491,692, filed August 12, 1921, there is disclosed self-contained apparatus in which the X-ray tube and the casing containing the transformer or other source of energy are carried upon a single support. By mounting the casing high enough upon the support, it will be above the heads and arms of persons in the room and the danger of accidents from contact with high-tension parts will be avoided. The transformer and the tube are caused to occupy always the same relative angular position upon the support.

As the transformer and the tube thus rotate together, the conductors connecting their respective terminals rotate with them, so that their relative position remains unchanged.

Among features of the present invention, a regulator for the X-rays is mounted upon the transformer casing up out of harm's way. The regulator may be controlled by the hand of the operator positioned near the tube. An indicator, such as a meter, is mounted upon the casing so as to rotate therewith, thus always presenting its face to the operator positioned near the tube in all positions of adjustment of the latter. These and other features will be understood by a consideration of the present invention as embodied, in its preferred form, in the X-ray apparatus hereinafter described, illustrated in the accompanying drawings and defined in the appended claims.

In the drawings:

Fig. 1 is a view in elevation of the upper portion of an upright showing an X-ray generator and a transformer casing mounted thereon, with parts attached according to a preferred embodiment of the present invention;

Figs. 2, 3 and 4 are, respectively, rear, side and front elevations of a portion of the apparatus shown in Fig. 1; and

Fig. 5 is a fragmentary view, partly in section, of a casing for the X-ray generator and associated parts.

An X-ray generator, shown as an electronic tube 2, and a source of energy for the generator, preferably a transformer, contained within a casing 4, are mounted inde-

pendently of each other upon a single support, shown as a hollow, movable upright 6. Self-contained apparatus is thereby provided that may be moved from place to place as a unit, where and when desired. The casing 4 is preferably mounted upon the top of the upright, so that persons in the room may not accidentally come into contact with the high-potential parts contained therein.

In order to adapt the apparatus for use upon objects variably positioned within wide limits, the X-ray tube is adjustable in a plurality of directions. It may be adjusted horizontally towards and from the upright along tracks 8. It may be adjusted angularly or rotatably about an axis at right angles to the upright. It may be adjusted vertically by running the tracks 8 up and down along the upright 6. And it may be adjusted angularly about the upright by swiveling the tracks thereabout as a unit. The tracks 8 may be locked in vertically and angularly or rotatably adjusted position along and about the upright by a clamp (not shown) that is manually controlled by a hand lever 23.

The terminal 12 at the anode end of the X-ray tube 2 is connected to a point 14 of the casing 4 by a conductor 16. The terminal 18 at the cathode end of the tube is similarly connected to points 20 and 22 by conductors 24 and 26. The point 14 is connected to a terminal of the source of energy (not shown) contained within the casing 4 and the points 20 and 22 are connected to other terminals thereof. The conductor 16 may be held separated from the conductors 24 and 26 by spreaders 32 and 34. The spreaders 32 and 34 may be adjusted to hold the conductors nearer together or farther apart than shown in Fig. 1, as desired, but the use of the spreaders alone will not suffice to prevent crossing of the conductors when the X-ray tube is adjusted rotatably about and vertically along the upright, horizontally to and from the upright, and during other adjustments of the tube. As two of the conductors are of very high potential, such crossing may result in rupturing the insulation covering the conductors, and the causing of a short circuit, with possibly serious damage.

According to the invention disclosed in the above-named application, when the X-ray tube is angularly or rotatably adjusted

about the upright, the rotative movement is communicated to the casing 4. The relative angular positions of the generator and the casing and, therefore, of the conductors also, are thus maintained substantially unchanged. To this end, the casing 4 is rotatably mounted upon the top of the upright 6, ball bearings, not shown, being interposed. The casing 4 is provided with a bracket 38 upon which is mounted a pulley 40. One end of a flexible cable or chain 42 that is mounted over the pulley is fastened to adjustably support the tracks 8, and the other end is secured to a counterweight 44 within the hollow upright 6. The counterweight approximately balances the weight of the tracks 8 and the parts carried thereby in any position of vertical adjustment along the upright. As the tracks 8 are angularly or rotatably adjusted horizontally about the upright 6, the counterweight, acting through the cable 42 and the bracket 38, causes the casing 4 at the top of the upright to become angularly adjusted to correspond, the rotative movement of the tracks 8 becoming thus communicated to the casing.

In this manner, crossing of the conductors 16, 24 and 26 is prevented during the rotative adjustment of the tube 2 about the upright 6. To prevent their crossing during the vertical, horizontal and other adjustments of the tube, they are not allowed to become slack, but are always drawn taut. This result is attained, according to the present invention, by providing spring-controlled reels 46, 48 and 50, upon which the conductors 16, 24 and 26 are respectively wound. When the tracks 8 and the tube carried thereby are lowered, the reels are caused to unwind, in opposition to the action of their controlling springs. When the tracks are raised, the reels wind up again. Similar effects are obtained when the tube 2 is moved away from, or is returned towards, the upright along the tracks 8, and during other adjustments of the tube. The reel 46 is detachably mounted upon the end of a bracket 52 secured to and extending out on one side, beyond the casing 4. The reels 48 and 50 are detachably mounted upon a plate member 54 that is detachably secured to the front of the casing, as shown in Fig. 1.

A regulator 56 for the filament-heating current is mounted upon the back of the plate 54, where it may not be accidentally disturbed. The regulator is shown as a rheostat having a contact member 58. Two cords, 60 and 62 are secured to opposite ends of the contact members 58. The cord 60 leads over a pulley 64 and down into and through a guide 66, positioned along a track 8. The cords 60 and 62 may thus be manipulated by the operator stationed in front of the tracks 8 near the tube 2. Weights 68 and 70 are secured to the free ends of the cords

to maintain the cords taut during the vertical adjustment of the tracks 8. The weights 68 and 70 are differently colored or made otherwise distinguishable, so that the operator may be enabled to tell at a glance which cord to pull when he desires to increase or decrease the filament-heating current. By this arrangement, the regulating means is detachably located out of harm's way, near the source of energy, but it is controlled by means positioned near the X-ray tube.

A suitable milliammeter 72 indicates the strength of the current employed. It is mounted upon the casing 4 so as to rotate therewith, thus always presenting its face to the operator stationed in front of the tube 2 in all positions of adjustments of the latter.

The invention comprises also a novel tube mounting illustrated in Fig. 5. The tube is carried in a tube casing or holder 74 that is adapted to be firmly secured in place, between clamp blocks 76 and 78 of insulating material. The clamp blocks 76 may be telescopically adjusted up and down on their supports 80 to vary the distance of the tube 2 from the opening 82. The clamp blocks 78 may be removably clamped in position upon the tube holder 74 by nuts or the like 84. A very convenient tube support is thus provided, permitting ready removal of the X-ray tube, and as ready replacement of the same, in adjusted position.

Modifications will occur to persons skilled in the art, and all such are considered to be within the spirit and scope of the invention, and are intended to be included within the appended claims.

What is claimed as new is:

1. X-ray apparatus comprising a support, an X-ray generator rotatably mounted upon the support, a casing rotatably mounted upon the support containing a source of energy for the generator, the casing having spaced-apart points to which the source of energy is connected, the generator having spaced-apart terminals, a meter mounted upon the casing, conductors connecting corresponding terminals of the generator and said spaced-apart points, the conductors being drawn taut, and means whereby rotative movement of the generator will be communicated to the casing and the meter and crossing of the conductors will thereby be prevented.

2. X-ray apparatus comprising an upright, an X-ray generator rotatably mounted upon the upright, a casing rotatably mounted upon the top of the upright containing a source of energy for the generator, means for regulating the X-rays generated by the generator mounted upon the casing, means positioned near the generator for controlling the regulating means, an indicator for indicating the character of the X-rays generated by the generator mounted upon the

casing, and means whereby rotative movement of the generator is communicated to the casing.

- 5 3. X-ray apparatus comprising a support, an X-ray generator mounted upon the support, a casing mounted upon the support above the generator containing a source of energy for the generator, the casing having spaced-apart points to which the source of 10 energy is connected, the generator having spaced-apart terminals, a member mounted upon the casing at one of said points, conductors connecting corresponding terminals of the generator to the member and to the 15 other of said points, means for regulating the X-rays generated by the generator mounted upon the member, and means for controlling the regulating means positioned near the generator.
- 20 4. X-ray apparatus comprising a support, an X-ray generator movably mounted upon the support, a casing mounted upon the sup-

port above the generator containing a source of energy for the generator, the casing having spaced-apart points to which the source of energy is connected, the generator having spaced-apart terminals, a member detachably mounted upon the casing at one of said points, conductors connecting corresponding terminals of the generator to the member and to the other of said points, means for maintaining the conductors taut irrespective of the position of the generator upon the support, said maintaining means for one of the conductors being mounted upon the member, 30 means for regulating the X-rays generated by the generator mounted upon the member, and means for controlling the regulating means positioned near the generator.

In testimony whereof, I have hereunto 40 subscribed my name this 22 day of August, 1921.

CHARLES E. CAMPBELL.
